UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

DOOR.

1,282,146.

Specification of Letters Patent.

Patented Oct. 22, 1918.

Application filed March 8, 1917. Serial No. 153,246.

To all whom it may concern:

Be it known that I, CHARLES C. TOMKINSON, a citizen of the United States, and a resident of Plainfield, county of Union, and 5 State of New Jersey, have invented certain new and useful Improvements in Doors, of which the following is a specification, reference being had to the accompanying drawings, forming a part thereof.

10 My invention relates to sectional doors which are elevated in opening and transfer a portion of the weight to an auxiliary support. Furthermore, it has special reference to large, heavy doors which are adapted for 15 warehouses, pier sheds and the like.

One object of my invention is to equip a sectional door of the aforesaid character with a movable member, such as, for example, an arm or lever which is adapted to be retracted 20 when the door is closed and automatically moved into position to engage a bracket or other suitable auxiliary support when the door is in its open position.

Another object is to provide a folding door 25 having a movable arm or other member which is adapted to be moved in response to the relative movement or folding action of the door sections into a position to engage a stationary bracket or other auxiliary support 30 when the door is opened.

In order that my invention may be thoroughly understood I will now proceed to describe the same in the following specification, and then point out the novel features thereof 35 in appended claims.

Referring to the drawings:

Figure 1 is a sectional elevation of a door equipped with one embodiment of my invention.

40 Fig. 2 is a view corresponding to Fig. 1, but showing the door in its open instead of in its closed position.

Fig. 3 illustrates a modified door structure 45 which also embodies my invention. This is also a sectional elevation and corresponds to Fig. 2 except that the door is not completely opened.

In the drawings, 10 designates a post and 50 11 the lintel of a door frame. The door comprises an upper section 12 hinge-connected above the lintel at 13, an intermediate section 14 connected by hinges 15 to the section 12 and a sliding bottom section 16. My in-

vention is equally applicable to two section doors and in fact is applicable to doors of various types.

In the arrangement shown the intermediate section 14 has guideways 17 in which the bottom section runs and the bottom section has rollers 18 or other projections which engage the door posts and may coöperate with guides (not shown) thereon in a well known manner.

Secured to the upper door section 12 is a bracket 20 on which a bell crank lever having arms 21 and 22 is pivotally mounted. The arm 21 of the bell crank lever has an extension 23 with which one end of a spring 24 is connected. The other arm 22 has a roller or wheel 25 which is adapted to engage 70 a suitable auxiliary support, such as the stationary bracket 26, which is suspended from ceiling beams 27 and may form part of the ceiling structure. The hoisting mechanism for the door may be of the usual type and is 75 designated 28.

A link 29 is pivotally connected at 30 to the intermediate door section 14 and is provided with a slot 31 near its opposite end which provides a lost motion connection between 80 the link and the arm 21 of the bell crank lever. The other end of spring 24 is connected with this link 29 at 32. The arrangement of parts is such that when the door is shut, as shown in Fig. 1, the arm 21 is substantially parallel to the plane of the door section 12, and when the door is opened the bell crank lever will be swung into the position illustrated in Fig. 2, as soon as it is in 85 position for its roller 25 to ride on top of the support 26 with the arm 21 substantially perpendicular to the plane of the door section 12.

In other words, the bell crank lever is 90 swung by the link 29 relative to the door section when the door section is completely opened so that the roller arm is substantially parallel to the plane of the door section 12 and extends outwardly beyond the door section into engagement with the stationary 100 support 25.

The lost motion provided by the slot 31 allows for an increase of the distance between the pivotal connection 30 and the pin on bell crank lever arm 21 during a part of 105 the folding movement of the door sections,

without pulling the arm 21 back, as the backward movement of the arm may be limited.

The door shown in Fig. 3 in which corresponding parts are designated by the same reference characters, is provided with a bell crank lever 33 pivoted at 34 on the upper door section 12 and connected to an arm 35 which is mounted to slide in a bracket 36 near the bottom edge of the upper door section 12.

A roller 37 is mounted on the arm 35 near its outer end which extends beyond the bracket 36 and a spring 38 is arranged to retract the arm 35 and hold the roller 37 close to the bracket 36 except when the door is fully opened.

The complete closing of the section 14 upon the section 12 actuates the downwardly extending arm 39 of the bell crank lever 33 and forces the arm 35 outward in opposition to the spring 38. The roller 37 then rides onto the stationary support 26 and constitutes a simple and effective means for transferring a part of the weight of the door to the auxiliary support.

Various structural modifications may be effected within the spirit and scope of my invention, and I intend only such limitations as are indicated by the appended claims.

What I claim is:

1. A door adapted to be elevated to open, a stationary support adapted to sustain a part of the weight of the door when open, and a relatively movable member mounted on the door and means for actuating said member into position to engage said support when the door is opening and retracting said member when the door is closing.

2. A door adapted to be elevated to open, an auxiliary stationary support adapted to sustain a part of the weight of the door when open, and a relatively movable member mounted on the door and means for actuating said member into a position to engage the auxiliary support, by the movement of the door in opening and retracting said member by the movement of the door in closing.

3. A door comprising sections adapted to be folded and elevated in opening, a stationary support adapted to sustain a part of the weight of the door when open, and a member actuated into position to engage said support by the relative movement between the door sections in opening and retracted in closing.

4. A door comprising sections adapted to be folded and elevated in opening, a stationary support adapted to sustain a part of the weight of the door when open, and a relatively movable member mounted on the door and actuated into position to engage the stationary support by the relative movement of the sections in folding and retracted when the sections are unfolded.

5. A door adapted to be elevated to open, a stationary support adapted to sustain a part of the weight of the door when open, and a lever pivotally connected to the door and arranged to be actuated by the movement of the door in opening, into position to extend beyond the door to coöperate with the support when the door is open.

6. A door comprising sections adapted to be folded and elevated in opening, a stationary support adapted to sustain a part of the weight of the door when open, and a lever pivotally mounted on one of the door sections and adapted to be actuated by the other section in opening, into position to extend beyond the door to engage said support when the door is open.

7. A door comprising sections adapted to be folded and elevated in opening, a stationary support adapted to sustain a part of the weight of the door when open, and a bell crank lever pivotally mounted on one of the door sections adjacent to the edge which swings away from the door frame in opening, and a mechanical connection between the bell crank lever and another section of the door, arranged to turn the bell crank lever into position to engage said support when the door is opened.

8. A door comprising a pair of hinge-connected sections adapted to be folded and elevated in opening, a stationary support adapted to sustain a part of the weight of the door when open, and a member mounted on one of the sections near their connected edges and connected to be actuated by the movement of the other section relative thereto, into position to engage said support.

9. A door comprising a pair of hinge-connected sections adapted to be folded and elevated in opening, a stationary support adapted to sustain a part of the weight of the door when open, a bell crank lever mounted on one of the sections adjacent to their connected edges and an actuating link connecting the bell crank lever with the other section, whereby the relative movement between the sections in opening swings the bell crank lever into position to engage said support.

10. A door comprising a pair of hinge-connected sections adapted to be folded and elevated in opening, a stationary support adapted to sustain a part of the weight of the door when open, a bell crank lever mounted on one of the sections adjacent to their connected edges and an actuating link connecting the bell crank lever with the other section, whereby the relative movement between the sections in opening swings the bell crank lever into position to engage said support; and means for retracting the bell crank lever as the door is closed.

11. A door comprising a pair of hinge-connected sections adapted to be folded and ele-

vated in opening, a stationary support adapted to sustain a part of the weight of the door when open, a bell crank lever mounted on one of the sections adjacent to 5 their connected edges, an actuating link between the bell crank lever and the other section and comprising a lost motion connection, whereby the relative movement between the sections in opening swings the bell 10 crank lever into position to engage said support, and retracts the bell crank lever as the door is closed and a spring between said bell crank lever and said link.

12. A door adapted to be elevated to open, a stationary support adapted to sustain a 15 part of the weight of the door when open, an arm secured to the door and movable beyond the outer edge of the door when open, and a member adapted to fold as the door is opened and actuate the arm to engage said support. 20

In witness whereof, I have hereunto set my hand this 6th day of March, 1917.

CHARLES C. TOMKINSON.

Witnesses:

HENRY SHANZ,
I. B. MOORE.
